COMBINATION LUNCH KIT AND HANDBAG

Carl W. Sundberg, Birmingham, and Montgomery Ferar, Huntington Woods, Mich.

Application October 30, 1950, Serial No. 192,848

4 Claims. (Cl. 206—4)

1

The present invention relates to a lady's general utility case which is designed to permit a working girl to carry her lunch therein and has the outward appearance of a lady's purse, and which serves the dual purpose of being a purse as well as a lunch kit. This invention is a modified form of the general utility case disclosed in our copending application, Serial No. 163,026, filed May 19, 1950.

It is among the objects of the present invention to provide a lady's general utility case which is constructed and arranged to be used simultaneously as a lunch kit and a lady's purse, and which is characterized by the novel arrangement of the compartments therein and the locations of the means for gaining access into said compartments, whereby the optimum functional benefits for which said general utility case is constructed and arranged may be derived; and further, which case is characterized by the efficient utilization of space therein, thereby to provide a case having a relatively large carrying capacity without having the appearance of being unduly large.

It is another object of the present invention to provide a general utility case fabricated from a suitable plastic material, or the like, which case will have the outward appearance of a lady's handbag while being adapted to be used to carry a lunch therein and to serve as a purse, and which can be fabricated by mass production methods from relatively few and simple parts to enable the cost thereof to be relatively low while permitting an attractive utility case to be produced.

Other objects of this invention will appear in the following description and appended claims, reference being had to the accompanying drawings forming a part of this specification wherein like reference characters designate corresponding parts in the several views.

In the drawings:

Fig. 1 is a perspective view of a preferred embodiment of the general utility case of the present invention;

Fig. 2 is a perspective view of the general utility case shown in Fig. 1 with the lunch compartment and the door of the purse compartment being open; and

Fig. 3 is another perspective view of the general utility case, drawn to a reduced scale, with the lunch compartment open and with a vacuum bottle being shown therein.

Before explaining the present invention in detail it is to be understood that the invention is not limited in its application to the details of construction and arrangement of parts illustrated in the accompanying drawings, since the invention is capable of other embodiments and of being practiced or carried out in various ways.

Also it is to be understood that the phrasology or terminology employed herein is for the purpose of description and not of limitation.

Referring to the drawings, a preferred embodiment of the present invention can be seen wherein the general utility case is identified by the reference numeral 10. The general utility case 10 has a purse compartment 12 in its upper portion and a lunch compartment 14 in its lower portion. The lunch compartment 14 has a chamber 16 within which a vacuum bottle 18 or the like, can be contained. A chamber 20 is also provided in the lunch compartment 14 for carrying sandwiches or the like. A shoulder strap 22 has its ends connected to the opposite ends of the utility case 10 to enable the user of the utility case to carry the same.

The utility case 10 has an inverted L-shaped section 24 which includes the cross member 26 and the leg member 28. The cross member 26 has the purse compartment 12 formed therein and a door 30 is hingedly connected as at 31 to form the upper wall of the purse compartment 12.

If desired, the door 30 can be maintained in a closed position by a lock construction which includes the clip 33 which can be snapped over the outwardly projecting portion 34 to be recessed in the groove 36 formed in the portion 34. However, it should be understood that any other form of locking means may be used with the present invention.

The leg portion of the inverted L-shaped member 24 has endwalls 38 and 40 and a sidewall 42. Another section member 44 is hingedly connected at 32 to the inverted L-shaped member 24 and is constructed and arranged to close the inner open side of the latter member. As can be seen, the section member 44 has endwalls 46 and 48 and a sidewall 50. The endwalls 46 and 48 are adapted to abut against the endwalls 38 and 40, and the upper edge 52 of the section member 44 is adapted to engage the under edge 54 of the cross member 26 to provide the closed lunch compartment 14 when the endwalls 38 and 40 and the endwalls 46 and 48 are in abutting relationship.

The chamber 16 provided within the lunch compartment 14 is formed by means of the pair of walls 56 and 58 which are arranged within the inverted L-shaped member 24 and the section member 44 respectively. These walls 56 and 58 are spaced an equal distance above the hinge connection 32 so as to be substantially in abutting relationship when the lunch compartment 14 is closed, and the walls 56 and 58 are spaced a sufficient distance above the hinged connection to provide a chamber within which the vacuum bottle 18 can be contained. The chamber 16 is relatively smaller than the remaining cham-

ber 20 within the lunch compartment 14, and the latter chamber is provided so that sandwiches and the like, can be carried therein.

A relatively simple locking device is provided for locking the lunch compartment 14. The locking device includes a lug 60 which is adapted to fit within the cut away portion 62 in the lug 64. A clip 66 is pivotally mounted in the lug 64 and is adapted to be snapped over the lug 60 and over the lower portion of the lug 64 to be seated in the groove 68 in the lower portion of the two lugs. Again it should be understood that other suitable locking means may be used if desired.

The inverted L-shaped member 24 of which the door 30 is considered a part and the section member 44 are preferably constructed from any suitable type of plastic material. In fabricating these parts, a suitable decorative finish can be formed on the outer surfaces. However, it is contemplated that suitable covering such as alligator skins or the like, may be used for covering the outer surfaces of the utility case, if desired.

From the above description, it can be seen that a lady's general utility case has been provided having a purse compartment in the upper portion, which purse compartment is readily accessible for use at all times by the person carrying the utility case. The purse compartment can be used at any time without the necessity of opening the lunch compartment and is sufficiently large to carry the various articles normally carried in ladies' purses. The general utility case is constructed to provide a well-balanced unit, since the vacuum bottle is carried in the lower portion of the case. The general utility case is also constructed so that the lunch compartment can be completely opened and the lunch can be eaten without removing the contents of the lunch compartment and placing them on a table, lunch counter, or the like.

Further, it can be seen that this lady's general utility case is made from a relatively few parts which can be easily constructed and easily assembled so that a utility case of relatively low cost can be fabricated. Further, it is designed to utilize the space therein to the greatest advantage and to permit an attractive case to be provided.

Having thus described our invention, we claim:

1. A lady's general utility case comprising an inverted L-shaped section having a compartment in its cross member and with the leg thereof being hollow and open on the inner side, another section hingedly connected with the inverted L-shaped section along the respective lower edges of the sections, the second-named section being hollow and open on the side adjacent the first-named section with the edges of the respective open sides being in abutting relationship to form a compartment under the compartment in said cross member, and substantially horizontally disposed walls formed in each of said sections an equal distance above the hingedly connected edges to form two chambers within the second-named compartment.

2. A lady's general utility case comprising an inverted L-shaped section having a compartment in its cross member and with the leg thereof being hollow and open on the inner side, another section hingedly connected with the inverted L-shaped section along the respective lower edges

of the sections, the second-named section being hollow and open on the side adjacent the first-named section with the edges of the respective open sides being in abutting relationship to form a compartment under the compartment in said cross member, and substantially horizontally disposed walls formed in each of said sections an equal distance above the hingedly connected edges to form two chambers within the second-named compartment, said first-named compartment having a hingedly connected door forming the upper wall thereof.

3. A lady's general utility case comprising an inverted L-shaped section having a compartment in its cross member and with the leg thereof being hollow and open on the inner side, another section hingedly connected to the inverted L-shaped section along the respective lower edges of the sections, the second-named section being hollow and open on the side adjacent the first-named section with the edges of the respective open sides being in abutting relationship when the sections are in a closed position to form a compartment under the compartment in said cross member, the upper side of said second-named section being open with the edges of the opening being in engagement with the lower edges of said cross member when said sections are in a closed position, and substantially horizontally disposed walls formed in each of said sections an equal distance above the hingedly connected edges to form two chambers within the second-named compartment.

4. A lady's combination lunch kit and purse comprising an inverted L-shaped section having a purse compartment in its cross member and with the leg thereof being hollow and open on the inner side, another section hingedly connected to the inverted L-shaped section along the respective lower edges of the sections, the second-named section being hollow and open on the side adjacent the first-named section with the edges of the respective open sides being in abutting relationship to form a lunch compartment under said purse compartment, substantially horizontally disposed walls formed in each of said sections an equal distance above the hingedly connected edges to form two chambers within the lunch compartment, the lower chamber being adapted to receive a vacuum bottle, said purse compartment having a hingedly connected door forming the upper wall thereof, means for locking said door in a closed position, and means for locking said sections together in a closed position.
